UNITED STATES PATENT OFFICE.

ELLIS E. ERICKSON, OF IRVINGTON, NEW JERSEY, ASSIGNOR TO NEWARK SIGN COMPANY, OF NEWARK, NEW JERSEY, A CORPORATION OF NEW JERSEY.

DESIGN FOR AN OUTDOOR SIGN.

52,007.

Specification for Design.

Patented May 7, 1918.

Application filed April 3, 1917. Serial No. 159,553. Term of patent 7 years.

To all whom it may concern:

Be it known that I, ELLIS E. ERICKSON, a citizen of the United States, residing in Irvington, county of Essex, and State of New Jersey, have invented a new, original, and ornamental Design for Outdoor Signs, of which the following is a specification, reference being had to the accompanying drawings, which form a part thereof.

The figure is a front view of an outdoor sign illustrating my new design. At opposite ends of the signboard proper are end posts *a* each of which is surmounted by a

top *b*, there being an elongated panel *c*, having angular upper and lower ends, on the face of each post.

I claim—

The ornamental design for an outdoor sign, as shown and described.

In testimony of which invention I have hereunto set my hand, at Newark, N. J., on this 20th day of March, A. D. 1917.

ELLIS E. ERICKSON.
